UNITED STATES PATENT OFFICE.

MARK A. RICE, OF LOS ANGELES, CALIFORNIA.

WRENCH.

1,218,316.

Specification of Letters Patent.

Patented Mar. 6, 1917.

Application filed August 22, 1916. Serial No. 116,271.

To all whom it may concern:

Be it known that I, MARK A. RICE, a citizen of the United States, and a resident of Los Angeles, in the county of Los Angeles 5 and State of California, have invented certain new and useful Improvements in Wrenches, of which the following is a specification.

My invention relates to wrenches, and the main object thereof is to provide an adjustable wrench possessing substantially the rigidity of a solid wrench. The ordinary adjustable wrench is unreliable for close work on account of lost motion and the loose movement of the several parts, and will not maintain a perfect adjustment necessary to satisfactory work, particularly on small hexagon nuts. With my invention, however, I overcome this tendency to lost motion and the tendency of the parts to work loose after the wrench has been used some time and I accomplish this result without any change in the stock or jaws of adjustable wrenches now on the market, the only change being in the screw-threaded jaw adjusting means.

My invention is fully described in the following specification, of which the accompanying drawings form a part, in which like characters refer to like parts in each of the views, and in which:—

Figure 1 is a side elevation of one type of adjustable wrench provided with my invention; and

Fig. 2 is an enlarged section taken on the line 2—2 of Fig. 1.

Referring to the drawings, 3 represents a stock provided with a fixed jaw 4, with an opening 5 entirely therethrough transversely thereof, and with a passage 6 for the screw-threaded carrier for a movable jaw 7, said carrier being designated 8 and being of substantially T-formation in cross-section to prevent its escape from the similarly formed passage 6 except axially of said carrier.

The opening 5 in the stock is of conventional form, as are all the parts so far mentioned, said opening being for the reception of the threaded element or nut 9 which is in constant engagement with the threads on the carrier 8 and moves said carrier axially

when said nut is manually rotated, thereby adjusting the jaws toward or from each other correspondingly, this nut also being of the ordinary type exteriorly.

By reference to Fig. 2, enlarged over Fig. 1, it will be observed that the nut 9 is held in place by means of a screw 10 in turn held in the stock above and below the opening 5, this also being of ordinary construction, but I provide a recess 11 in the nut 9 for the reception of a coil spring 12 through which the screw 10 is freely passed, and I provide a cap 13 for this recess 11 which serves as a bearing for the upper end of the coil spring 12 and is in turn held against the stock at the upper side of the opening 5.

In order to provide against relative movement of the nut 9 and cap 13 I slot the upper end of the nut, at 14, for a slight projection 15 on the cap, the latter having approximately the same external diameter as the internal diameter of the recess 11 and projects thereinto.

The action of the coil spring 12 tends to force the cap away from the nut and thus into frictional contact with the stock, and the spring also tends to force the lower end of the nut into stock contact for the same reason, with the result that, while the nut may be manually rotated when desired, such a strong frictional contact with the stock is maintained which contact prevents any tendency on the part of the nut to rotate independently and thus permit the jaws to separate.

Further, because of the extreme simplicity of the construction, my invention is applicable to wrenches of different types, and I reserve the right to make all such changes in details as will be necessary to adapt the invention to other types of wrenches, provided such changes do not depart from the spirit of the invention, and come within the scope of the following claim.

Having fully described my invention, what I claim as new, and desire to secure by Letters Patent, is:—

A wrench, comprising a stock provided with an opening therethrough, a fixed jaw thereon, a jaw movable therein, a rotating

nut in said opening in operative engagement with said movable jaw, a screw held in said stock and passed through said nut, a spring contained within said nut, said 5 nut being counterbored to receive the same and being slotted at the outer end, and a cap on said nut having a part thereof within said

counterbore and a projection thereon held in said slot to prevent relative rotation, said spring forcing said nut and cap apart into 11 frictional engagement with said stock at opposite ends of said opening.

MARK A. RICE.
